UNITED STATES PATENT OFFICE.

WALTER WESTPHAL, OF LOS ANGELES, CALIFORNIA.

RADIO LOUD SPEAKER.

Application filed March 30, 1926. Serial No. 98,502.

My invention is a radio loud speaker and in the mechanism for vibrating a diaphragm by means of an electric current, the invention being principally in the manner of mounting 5 an electric-magnetic device in relation to the diaphragm to vibrate same in accordance with the electric current from a radio receiving instrument.

An object of my invention is to manufacture the holding device for the diaphragm, to make a magnet, pole pieces, a spool, etc., on which the windings of an electro-magnet are wound so that practically all the elements may be made by die-pressing, reducing 15 to a minimum extent the amount of machine cutting or filing etc., that may be necessary.

In the structure of my loud speaker, an object of my invention is to utilize a flat 20 horseshoe magnet to secure die-pressed pole pieces to opposite ends of the magnet, these pole pieces being utilized to properly center an electro-magnet wound on a spool, the spool being formed by die-pressing and 25 soldering and to mount an armature directly in the spool without the necessity of a sleeve or the like around the armature. I utilize a bolt in the ordinary manner to transmit the vibrations from the armature to the dia- 30 phragm.

My invention will be more readily understood from the following description and drawings, in which;

Figure 1 is a plan view of my loud speaker 35 taken in the direction of the arrow 1 of Fig. 2;

Fig. 2 is a vertical section on the line 2-2 of Fig. 1.

Fig. 3 is an end view of the horseshoe 40 magnet illustrating the pole pieces broken away, and showing the diaphragm holder in elevation, the view being taken substantially in the direction of the arrow 3 of Fig. 1;

Fig. 4 is an elevation taken in the direction 45 of the arrow 4 of Fig. 1;

Fig. 5 is a side elevation of the elements of the spool before being connected together;

Fig. 6 is an end view of the elements of 50 the spool viewed in the direction of either of the arrows 6 of Fig. 5;

Fig. 7 is a plan of the upper section of

the spool frame, taken in the direction of the arrow 7 of Fig. 5;

Fig. 8 is a bottom view of the upper section of the spool frame taken in the direction of the arrow 8 of Fig. 5;

Fig. 9 is a longitudinal section of the spool frame assembled.

Fig. 10 is an alternative construction of a 60 spool showing an alternative mounting for the armature.

Attention is first directed to the construction of the diaphragm holder on which the electro-magnet to vibrate the armature is 65 supported. A supporting plate 1 is preferably made circular and is formed in a die-press forming a substantially flat plate 2 with a tubular center part 3 through which the sound is conducted to a horn or the like. 70 The edges of the plate have an upturned rim 4. An annular indentation or groove 5 is formed by die-pressing from the outside, this pressing an annular ridge 6 upwardly. A gasket 7 rests on this ridge and the diaphragm 8 rests on the gasket. An upper gasket 9 is placed on top of the diaphragm and is wedged down tightly thereon by a clamping plate 10. This plate is also of circular construction and has a slightly downwardly pressed annular edge 11 through 75 which the securing screws 12 are fastened.

There is a slight space between the supporting plate and the clamping plate as indicated by the numeral 13 so that these plates 80 can be tightly secured together by the screws 12. This clamping plate has a series of upwardly pressed nubs 14 adapted to position the magnet and pole pieces of the electro-magnet. The clamping plate has a central opening 15 to allow connection from the electro-magnet to the diaphragm as hereunder set forth.

The electro-magnet is constructed with a 85 horseshoe magnet 20, this latter being made flat with opposite poles in the same plane. A lower pole piece 21 is formed with a base 22, opposite sides 23 and an end 24. These sides and the one end are bent upwardly in a die-pressing operation. The lower pole 90 piece is secured to one pole of the magnet by means of a screw 25 which passes into the end 24.

The upper pole piece 26 has a top 27, op-

posite sides 28 and an end 29. The two sides and the single end are bent into shape in a die-pressing operation. The upper pole piece is secured to the opposite pole of the 5 magnet, to the lower pole piece, by means of a screw 30 extending through such pole and into the end 29. It will thus be seen that the pole pieces are rigidly secured to the opposite poles of the permanent magnet and 10 form upper and lower channels 31 and 32 in which the spool having electric wiring and the armature are inserted.

The spool and the manner of making same is substantially as follows, having reference 15 particularly to Figs. 5 to 9:

The spool has upper and lower sections 33 and 34, these being of similar construction and formed by die-pressing. The center portion 35 is flat, having slightly offset 20 pressed ends 36 with upwardly bent opposite sides 37. The sides at each end have outwardly extending flanges 38. The corners 39 may be cut off at an angle if desired or rounded.

25 As above mentioned, the two sections of the spool are formed similar so that when the spool sections are placed together the flanges 38 are slightly flared in an opposite direction as indicated by the numeral 40, 30 thus allowing filling with solder. The meeting edges of the spool sections indicated by the numeral 41 extending lengthwise of the flanges 38, and the cross edges 42 as clearly shown in Figs. 5 and 9, contact and are secured together by solder. The flanges as 35 above mentioned form a surface of considerable extent to which a sufficient body of solder may be secured to form a substantial spool.

40 It will thus be seen that when the spool elements are assembled, that a rectangular opening 43 extends from side to side of the spool as shown in Fig. 9. After the spool is constructed a cut 44 is made transversely 45 across the upper section of such spool, cutting the side walls 33 and the base or flat surface 35, as indicated by the dotted lines in Figs. 5 and 7 and by the full lines in Fig. 9.

50 The armature and the manner of securing same in place is substantially as follows, having reference particularly to Figs. 5, 7, 8 and 9:

The armature 45 is substantially rectangular having however, projections 46 at opposite ends. A slight groove 47 is cut in the lower surface of the armature and a plurality of drilled holes 48 at each end of the groove. The center portion or center plate 55 35 of the spool has a pair of drilled holes 49 to register with those of the armature and has a slightly counter-sunk portion indicated by the numeral 50 at the upper end of said drilled holes. A suspending wire 51 fits in the groove of the armature and ex-

tends through the holes in the armature and the center section of the upper part of the spool, being secured in position by solder in the counter-sinks 50 and solder securing the wire in the groove 47. The ends of the wire 70 are then clipped off, flush with the surface of the center section of the spool. This construction spaces the armature in the mid position of the opening 43 as shown in Fig. 9. The spool frame as thus formed is then 75 wound with the usual type of wiring, this being very fine enameled copper wire and the usual insulation 52 is placed between the copper of the frame and the wire.

The assembly of the pole pieces and spool 80 is substantially as follows, having reference particularly to Figs. 1 to 4:

As above mentioned the flanges of the spool frame are secured together by wire and form a stiff frame, these flanges being 85 slightly flared apart. The ends of the pole pieces fit against these flanges as indicated by the numerals 53 and 54; thus tightly securing the spool in the pole pieces. The ends 55 of the spool frame fit snugly in the 90 ends 24 and 29 of the pole pieces. The side of the spool frame is slightly spaced from the base 22 and the top 27 of the pole pieces as indicated by the numeral 56. A bolt 57 is secured to the center projection 46 of the armature, extends through the opening 50 in the clamping plate and is attached to the diaphragm as indicated by the numeral 58.

Usually the bolt is secured by solder to the projection 46 and has very fine threads at 100 its other end, and is adjustably secured to the diaphragm by means of thin threaded washers on opposite sides of the diaphragm and a lock nut on the lower side. The pole pieces are securely fastened to the clamping plate by means of rivets 59 which extend through the base 22 of the lower pole piece, these rivets having counter-sunk heads at both ends. The electro-magnet and the pole pieces rest on the nubs 14 upwardly pressed 110 from the clamping plate.

The electrical connectors are secured to a bolt 60 positioned centrally between the arms of the magnet; this bolt extending upwardly through the clamping plate. Each 115 of the connectors 61 is formed by a strip of metal having a punched-out tongue 62 with a screw 63 through the top, securing the terminus 64 of the electric lead wire in position. The lower connector is insulated from the 120 clamping plate and the connectors insulate from each other and from the nut on the bolt 60 by insulation washers 64. The free ends 65 of the connectors extend over the permanent magnet, having a strip 66 of insulation 125 therebetween. Thus the connectors function to hold the permanent magnet firmly in position in relation to the clamping plate. Electric leads 67 extend from the connectors 130 to the winding 68 of the spool.

From the above description it will be seen that practically all the elements of my loud speaker may be made by die-pressing the different parts, requiring very little machine work, filing or grinding. The operation is believed to be obvious, the fluctuations of the electric current causing the vibration of the armature, this being communicated through the bolt 57 to the diaphragm and vibrating the diaphragm.

Although the various elements of my loud speaker are of simple construction and assembled in a simple manner, it will be manifest that these may be materially altered to form different sized loud speakers and that the general construction and specific details may also be materially altered, such changes however, being within the spirit of my invention as set forth in the description, drawings and claims.

In Fig. 10 the spool is illustrated as provided with a hook 70 adapted to engage a complementary hook 71 on the armature. These hooks are so arranged that the armature is balanced when the hooks are in engagement and allow free tilting of the armature as it vibrates. The bolt 57 leading to the diaphragm prevents the armature from becoming unhooked from the hook in the spool, this action being aided by a bent pin 72 having one end fitting in a hole 73 in the upper pole piece; the free end of the pin having a free fit through an aperture 74 in the armature.

Having described my invention, what I claim is:

1. In a radio loud speaker, a U-shaped flat permanent magnet, a lower pole piece connected to one of the poles, an upper pole piece connected to the other pole, the said pole pieces being channel-shaped, a spool having electric wiring mounted in the pole pieces with a transverse opening therethrough, an armature suspended in the transverse opening of the spool, the pole pieces having a closed end, the closed end being secured to the poles of the magnet, the end of one pole piece being longer than the other, thereby positioning such pole pieces directly above the other.

2. In a radio loud speaker, a supporting plate of circular shape having an upwardly pressed annular groove on the outside forming an inwardly pressed ridge on the other side, a diaphragm resting on said ridge, a clamping plate bearing on the diaphragm, and means to secure the clamping plate and supporting plate tightly together, there being gaskets between the diaphragm and the supporting and clamping plates.

3. In a radio loud speaker as claimed in claim 2, having in addition an upwardly turned rim on the supporting plate, a downwardly pressed annular edge on the clamping plate, there being a series of screws

through the annular edge and the supporting plate forming a means to clamp same together.

4. In a radio loud speaker, a flat U-shaped magnet, a pair of channel-shaped pole pieces, the lowermost pole piece having an end closing one end of the channel, the end being secured to the inside of one of the magnet poles, the upper pole piece having an end longer than the end of the lower pole piece extending downwardly, closing one end of the upper pole piece, and being connected to the inside of the opposite pole of the magnet.

5. In a radio loud speaker, a spool having a pair of opposite flat sections spaced apart, side walls extending beyond said sections, the side walls being secured together by solder, the flat sections being spaced apart and forming a transverse opening.

6. In a radio loud speaker, a spool formed of complementary parts, each of said parts having a central flat section, inwardly pressed ends at the end of said section, adapted when assembled to form a transverse passage through the spool, there being side walls extending in opposite directions from the flat sections, outwardly extending flanges on the sides, the flanges being secured together.

7. In a radio loud speaker, a spool formed of complementary parts, each of said parts having a central flat section, inwardly pressed ends at the ends of said sections, adapted when assembled to form a transverse passage through the spool, side walls extending in opposite directions from the flat sections, wall extensions beyond the ends of said flat sections, and means to secure the wall extensions together.

8. In a radio loud speaker, a flat U-shaped magnet having parallel upper and lower faces, a pole piece having an end secured to one of the ends of the magnet on the inside, a channel member secured to said end with the base of the channel in alinement with the lower surface of the magnet, an upper pole piece having an end secured to the other end of the magnet and extending above the top of the magnet, a channel-shaped structure connected to the said latter end and extending over the lower channel pole piece, the sides of the channels being contiguous one to the other.

9. A radio loud speaker comprising in combination a supporting plate and a clamping plate having a central opening and a diaphragm clamped therebetween, a channel-shaped lower pole piece secured to the clamping plate, a flat U-shaped magnet having one pole secured to the said pole piece, the magnet being adapted to rest on the clamping plate, an upper pole piece longer than the lower pole piece secured to the opposite pole of the magnet, forming an in-

verted channel over the lower pole piece, a spool having a transverse opening therethrough and having an electric winding supported in the pole pieces, an armature in the 5 said opening, a bolt connecting the armature and the diaphragm, a plurality of electric connectors, a bolt securing said connectors to

the clamping plate, the free end of said connectors extending over the magnet, and adapted to hold said magnet tightly against 10 the clamping plate.

In testimony whereof I have signed my name to this specification.

WALTER WESTPHAL.
